UNITED STATES PATENT OFFICE.

GUSTRINE MILNER MABRY, OF BIRMINGHAM, ALABAMA.

TOY PICTURE BOOK.

Application filed October 6, 1924. Serial No. 741,882.

To all whom it may concern:

Be it known that I, GUSTRINE M. MABRY, a citizen of the United States of America, residing at Birmingham, in the county of 5 Jefferson and State of Alabama, have invented certain new and useful Improvements in Toy Picture Books, of which the following is a specification.

My invention relates to a toy picture book 10 which comprises one or more pairs of pages, each pair displaying on one side a picture associated with a movable tab which changes the pictorial representation when moved.

15 More particularly my invention contemplates forming each pair of pages of a single sheet folded transversely at its center and having its free end edges bound together or to the corresponding edges of 20 other pairs of pages in a book binding, and to dispose the movable tab in the fold of the sheet.

My invention further comprises a simple 25 and most effective manner for mounting the movable tab in the sheet at the least possible expense and to this end the page bearing the picture is slit and the movable tab is held by the tongues formed between the 30 slits in working relation with the sheet, the movable tab preferably having stops which by engagement with the tongues will prevent its removal or displacement.

My invention also comprises the novel 35 details of construction and arrangements of parts, which in their preferred embodiment only are illustrated in the accompanying drawings which form a part of this specification, and in which:—

40 Fig. 1 represents in partial perspective view a book formed of pairs of pages embodying my invention.

Fig. 2 is a detail view of the page illustrated in Fig. 1 showing the tab moved outwardly to change the pictorial representation.

45 Fig. 3 is a partial view of page 6 showing the manner of mounting the movable tab on the page.

Similar reference numerals refer to similar parts throughout the drawings.

50 I have shown my invention as embodied in book form, though it will be understood that each folded sheet forming a pair of pages constitutes a complete embodiment of my invention. I show these pairs of pages

1 and 2 formed by folding a sheet of paper across its transverse center and I bind the free end edges of the sheet in the backbone 3 of the book cover 4.

Each pair of pages are similar in their 60 physical structure but will differ in their pictorial representation. The drawings in Fig. 1 illustrate the back side of page 5 and the front side of page 6. On the back side of page 5 is displayed printed matter which 65 is descriptive of the pictorial representation on page 6. As illustrated, the subject of the pictorial illustration is the story entitled "The Little Red Hen".

The illustration on page 6 displays a 70 house 5 having a window opening 6 and a door opening 7, and projecting from one side of the house is the end of a movable tab 8. The subject matter displayed on this tab causes it to harmonize with the pictorial 75 matter underlying it or adjacent to it on the page so that it is not obvious and does not adversely affect the artistic and pleasing appearance of the page.

As will be seen in Fig. 2, to get the change 80 in the picture, the tab 8 is grasped and pulled outwardly to the right. In doing so the picture of the window closure 6, which was on the tab, moves out of register with the window and is replaced by the 85 picture of the little red hen. The representation of the door closure, which was also on the tab, moves out of register of the door opening and displays a dog.

This change in the picture is consistent 90 with the story and forms in many cases interesting and instructive matter for children.

In Fig. 3 I show the manner of mounting the movable tab on the page with which 95 it is associated. I provide a vertical slit 9 at the right hand side of the house and a corresponding slit 10 at the right hand side of the door opening 7. I also provide on the left hand side of the door opening a slit 11. 100 These slits 9, 10 and 11 are all, as shown, parallel and of equal size but it is only important that they be parallel. The exposed end of the tab is passed in front of the tongue between slits 10 and 11, behind the 105 tongue between slits 9 and 10 and has one end projecting on the outer side of the sheet. On each side of the window 6 I provide slits 12 and 13 which, as shown, are of less width than the other slits but stand parallel there- 110

with. I insert the other end 14 of the tongue 8 through the slits 12 and 13, causing it to pass in front of the tongue between said slits. I provide the tab preferably with 5 one or more shoulders 15 which exceed in length the several slits so that they will prevent the tongue or the tab being pulled out after it has once been mounted in the sheet.

Having made the tab as described and 10 bound the free ends of the sheet in the book or together, it is evident that access cannot be conveniently had of the tab to disengage it from the slits and tongues, and thus it will remain in position and it can be moved 15 back and forth to change the pictorial representation without fear of it being lost or displaced. Obviously the size of the tab and the arrangement of the slits will be largely governed by the pictorial representation, but in principle the tabs will always be mounted behind tongues formed by slits in the page, thus making as simple and inexpensive as possible the assembling of the book.

20 Though I have described with great particularity the details of the embodiment of the invention herein shown, it is not to be construed that I am limited thereto, as changes in arrangement and substitution of 25 equivalents may be made by those skilled in the art without departing from the invention as defined in the appended claims.

Having thus described my invention, 30 what I claim as new and desire to secure by 35 Letters Patent, is:—

1. A picture book of the character de-

scribed comprising a pair of bound pages connected at their free ends, one page having a pictorial display thereon and slits formed therein, a slide enclosed between the 40 pair of pages and woven through said slits and carrying pictorial matter displayed thereon which as the slide is moved will change the pictorial display, and a tab for shifting the slide which projects without the 45 pair of assembled pages.

2. A picture book in accordance with claim 1, in which the slide is provided with intermediate offset shoulders of greater width than the adjacent slits on both sides 50 thereof, said shoulders being adapted to limit the movement of the slide in both directions and prevent it being detached by a pull on its tab.

3. A picture book of the character de- 55 scribed, comprising a pair of pages formed by folding a sheet and binding the free end edges of the sheet, said sheet having on one exposed page surface thereof a pictorial representation, said page surface being pro- 60 vided with a plurality of parallel spaced slits, a slide mounted on the inner side of said slitted page within the fold of the sheet and woven through said slits with an end thereof projecting externally to manipu- 65 late it, said slide having pictorial matter thereon adapted to co-ordinate with and change the pictorial display in its several operating positions.

In testimony whereof I affix my signature.

GUSTRINE MILNER MABRY.
